UNITED STATES PATENT OFFICE.

ALEXANDER PALMROS, OF COLUMBUS, OHIO, AND EDWARD L. HOPKINS, OF ERIE, PENNSYLVANIA, ASSIGNORS TO THE JEFFREY MANUFACTURING COMPANY, OF COLUMBUS, OHIO, A CORPORATION OF OHIO.

MINING-MACHINE.

No. 889,149.

Specification of Letters Patent.

Patented May 26, 1908.

Application filed April 19, 1902. Serial No. 103,779.

To all whom it may concern:

Be it known that we, ALEXANDER PALMROS, of Finland, residing at Columbus, in the county of Franklin, in the State of Ohio, and 5 EDWARD L. HOPKINS, a citizen of the United States, residing at Erie, in the county of Erie, in the State of Pennsylvania, have invented certain new and useful Improvements in Mining-Machines, of which the following is a 10 specification, reference being had therein to the accompanying drawing.

Figure 1 is a plan view of a mining machine embodying the improvements. Fig. 2 is a 15 side elevation of the same, part of the machine being broken away. Fig. 3 is a section on the line x, x of Fig. 1. Fig. 4 is a section on the line y, y of Fig. 1. Fig. 5 is a longitudinal sectional elevation. Figs. 6, 7, 8, 9 and 10 show details.

20 The machine is made up of two principal parts, one being the bed frame, and the other being the carriage which slides forward and back on the bed, and carries the operative parts. The bed comprises longitudinal sill-like parts, and cross connecting parts at the front and rear. The side parts of the bed have the bottom bars A and the upper bars A'. The four side bars are at the front ends joined by cross connecting plate or bar, indicated as a whole by B. And at their rear ends they are joined by a connecting bar B'. The top bars A' are also straight from end to end. The bottom bars A extend from the rear forward some distance in the vertical planes of, and parallel with, the top bars A'. At points near the front end they are turned inward toward the central longitudinal plane of the machine.

40 The different parts of the bed frame of the present machine are particularly designed throughout to provide for the greatest strength with the least weight of metal. The top longitudinal bars A' and the bottom bars A are all made of angle irons, each with a web 45 or flange arranged vertically and a web lying horizontally. The front cross connecting part indicated by B is formed with a wide upper part d, and the central narrow standard part d', the latter having projections d² at the bottom. The upper part B is recessed at b³ to receive the upper side angle bars A'. The projections d² are similarly shouldered or recessed and joined at b⁴ to receive the bottom angle bars A.

B² is a bottom closing plate which extends 55 between the downwardly extending legs at d', thus inclosing the passage way through which moves the central supporting bar of the cutter carriage to be described.

The connecting piece B is shaped in such 60 way as to reduce metal and retain full strength. It is cast with a top, wider, part d, and bottom part b⁶, and a series of inclined braces b⁷ connecting the parts d and b⁶. Otherwise it is open, thus greatly reducing 65 the amount of metal in its construction.

The cross plate B² at the bottom is fitted by means of tongues b⁸ into grooves in the standards d' of the cross connecting part B''. The rear transverse connecting piece B' is 70 cast in such way that it receives the longitudinal bars at its corners. It is shaped to have a series of resting and holding places for the bracing device to be described which is applied at the rear end of the machine 75 when in use, these being indicated at b⁹, b¹⁰, b¹¹, b¹², there being adjacent to each, ribs or projections which hold the lower end of the bracing or fastening device in whichever position it is put. This construction permits 80 of the application of the brace or jack in longitudinal planes near one side of the machine, or near the other side, or central of it, thus permitting the machine to be firmly fastened in place according as the character 85 of the floor demands that the clamping pressure shall be applied at one point or another. The upper bars A' of the bed carry one element of the carriage feeding device, these, in this construction being rack bars D. 90 They are secured to the undersides of the bars A', and have their teeth turned downward.

The bed frame is constructed to furnish two guides for the carriage, an upper one 95 composed of the bars A', A', and the lower one consisting of the above described passage way in bottom part of the connecting bar B. The apparatus at the other end of the bed for clamping or fastening it firmly in place 100 is shown at E. In many respects it is substantially similar to those now in use, and does not require illustration or description in detail. It consists mainly of the coal engaging part e carried by the forked swinging frame e', and the part e is adapted to be forced by the nut wheel at e² against the coal 105 in front of the machine. But the present

holding device is superior to those heretofore used in machines of this sort, in that while the line of thrust of the coal engaging part e is inclined to the vertical planes of the machine, its point of contact is in the central longitudinal vertical plane, and not in a plane near the side of the machine as heretofore; and consequently the downward binding pressure can be evenly distributed across the front end of the machine, and the two sides can be held firmly in place. At the same time there is provided two mutually bracing legs e' , whereby the base of their attachment is extended. To receive these there are ears e^3 cast at or near the center of the front cross piece B, and ears e^4 near that end of the cross bar which is on the side opposite to that toward which the machine tends to be carried by the reaction of the cutters.

At E' is shown the rear jack or clamping device. It is formed with two diverging legs having sockets or ears at their inner ends, at such distances apart that they can be placed upon the resting and holding places at b^9 , b^{10} , b^{11} , or b^{12} on the rear connecting piece B'. If down pressure is principally wanted at the left side of the machine, the two legs are placed on the holding sections b^9 , b^{10} ; if the greater pressure is needed at the right hand side they are placed on the sections b^{11} , b^{12} ; if the center, they are placed at b^{10} , b^{11} . The ribs or projections on the bar B' prevent the legs from sliding laterally after they have been adjusted in position.

Upon the bed frame (constructed of the parts above described) is mounted the carriage, which moves back and forth thereon, and both actuates and advances the cutting apparatus.

F indicates a platform for supporting the shafting and gearing. It has elevated parts at f which rest upon the top of the side bars A' of the bed, and lips f' which lie on the outer side of the bed bars, and prevent lateral displacement. Between these side bar-like parts f , f' the platform drops to a relatively low plane, one of the purposes of the construction of the machine being to reduce the height to the utmost. G is an electric motor which also is arranged in a relatively low position, it being behind the platform F. Its armature shaft g is arranged horizontally and longitudinally of the machine, the commutator being at the rear end, and the gearing in front. The field metal of the motor is cast with wings for supporting and guiding plates G', substantially similar to the parts at f , f' of the platform F.

At g' , g' there are flanges or webs on the motor field metal by which it is firmly bolted to the platform.

It will be noted that the motor frame and the gear supporting platform or frame F are detachable from each other so that either

one may be removed from the bed frame without removing the other. This arrangement of parts permits the motor to be detached as an entirety without dismounting any of the power transmitting mechanism or the removal of all of the power transmitting mechanism on the power platform F and also the platform without dismounting the motor.

H indicates the cutting apparatus which consists of the endless chain h , having, at intervals, links, each provided with a cutter h' . This chain is arranged in a triangular form, and is supported upon a carrier (part of the general carriage) formed of the longitudinal bar I, and the cross head I'. At the rear end this chain carriage is adjustably secured to the platform F. The longitudinal bar I at the center is passed through the guide-way aperture in the lower part of the front cross connecting bar B. This bar I lies in horizontal planes considerably below those of the top guide-way formed by the top bars A'.

J is a sprocket wheel at the lower end of a vertical shaft j , which is mounted on the platform F; and with this sprocket wheel the cutter chain h engages. Shaft j is driven by the armature shaft, K being a large bevel wheel on the vertical shaft, and K' being a bevel pinion on the armature shaft meshing therewith.

When the motor is in action the shaft j drives the chain and the cutting of the coal is effected. Simultaneously with this the cutting apparatus can be moved longitudinally on the bed as follows: L is a transverse shaft on the carriage, and having pinions l , l' at its ends, each engaging with the aforesaid racks D on the bed A. This shaft is rotated slowly in one direction to feed the cutting apparatus forward and rapidly in the opposite direction to withdraw the carriage. To impart these two motions and speeds use is made of the following device: M is a supplemental or countershaft above shaft L. It is provided with a worm wheel m which engages with a worm m' on the shaft j . The worm wheel m and the shaft M are rotating in one direction whenever the motor and cutting chain are in action; but from the shaft M the different speeds and motions are taken. At one end of this shaft M there is a gear wheel N engaging with gear wheel N' on the shaft L. At O there is a clutch feathered to the shaft M, and adapted to engage with the gear wheel N, or with a disk thereon, said wheel and disk being otherwise loose on the shaft. Preferably, to economize room, the wheel and the disk are formed in the way shown, that is to say, each at the end of a journal or sleeve N², which is fitted in the bearing N³, there being two such bearings N³ and N⁴ for the shaft M, which are supported by standards M'.

The worm gearing is so designed as to give to the shaft L a relatively slow speed, and as this shaft is geared directly by the wheels N, N' to the carriage feeding shaft I, the latter will, to move the carriage forward, rotate correspondingly slowly. At the other end of the shaft M there is a mechanism for imparting to the carriage moving shaft L a higher speed in the opposite direction.

10 P is a gear wheel loosely mounted on the shaft M. It engages with a wheel P' on a supplemental shaft p behind the shaft M. Rigid with the wheel P' is the wheel P², which in turn meshes with the wheel P³ on the shaft L.

At R there is a second clutch adapted to engage with the wheel P, or a disk carried thereby; and when this clutch is in engagement the train of gearing from P to L will be set in motion, and the shaft L will be rotated in such way as to move the carriage backward with a relatively high speed.

T is a clutch shifting lever pivoted at t and extending back over the top of the motor G. It operates the clutches at O and R through the fork at r. There is also an automatic device for throwing the clutches at each end of the movement of the carriage.

R' is a sliding rod mounted in bearings at r' and r² at one side of the carriage. It engages loosely with a bell crank lever R² one arm of which is connected by a link R³ to the fork r of the shifting lever.

When the carriage reaches the front end of its travel, the rod R' strikes a projecting part r³ on the bed A' and pushes back on the bell crank lever R², and this throws the clutch O out of action, whereupon the carriage is arrested. Then the operator by means of lever T throws the other clutch R into engagement with the pull-back gearing, and thereupon the carriage is brought back to the rear of the bed. As soon as it reaches the rear end, the opposite end of the rod R' impinges upon another projection r⁴, and the clutch R is disengaged and left in its inactive position.

By arranging the motor and power transmitting devices connected therewith in the manner herein shown, we provide a machine which is relatively low and extremely compact, and is adapted particularly for use in low veins of coal. It will be seen that the shafting and gearing of the power transmitting mechanism for both the carriage and the chain is arranged substantially within the horizontal planes of the motor and that all the parts are readily accessible for adjustments or replacements. We are aware of the fact that it has been proposed to construct mining machines with the power transmitting devices for advancing the carriage and the cutter chain arranged at one side of the motor, but not entirely within the horizontal planes thereof.

A construction such as herein shown embodies the utmost economy of space vertically.

What we claim is:

1. In a mining machine, the combination with the cutting apparatus and the carriage, of the bed frame having the top longitudinal bars A', the front connecting cross bars, with an extension projecting down to the ground line at the central planes of the machine, and the bottom side bars A having their rear parts under and parallel to the top bars A, and turned inward at their front ends, and secured to the said central downwardly extending part of the front cross connecting bar to form inclined braces therefor, substantially as set forth. 70

2. In a mining machine of the character described, the combination with a suitable bed frame arranged to be securely held in position adjacent to the face of the material to be cut, a carriage arranged to travel forward and back on said bed frame and an endless cutting apparatus mounted upon the carriage, of a front brace or jack for the bed frame comprising a bar, the upper end of which is adapted to engage the material in front of the bed frame at a point in substantially the central vertical longitudinal plane of the machine, said bar extending rearwardly from said point away from the face of the material and toward the side of the machine on which the cutting apparatus travels rearwardly, and being supported by two arms, one pivoted at its lower end to the bed frame in the central longitudinal plane of the machine and the other pivoted to the bed frame at the said side thereof on which the cutting apparatus travels rearwardly. 85

3. In a mining machine of the class described, the combination of a bed frame adapted to rest upon the floor of a mine, a carriage mounted on said bed frame to move forward and back therealong, a suitably housed electric motor mounted upon said bed frame with its armature shaft disposed longitudinally thereof, said motor being suitably secured to said carriage and having its bottom side arranged closely adjacent to the ground-engaging supports for the bed frame, so as to travel forward and back in a horizontal plane closely adjacent to the floor of the mine, a cutting apparatus mounted upon said carriage and arranged entirely in front of the said motor housing, and shafting and gearing connecting said motor with said bed frame and cutting apparatus for moving the carriage along the bed frame and actuating the cutting apparatus, respectively, all of said shafting and gearing being confined at 100 one end of said motor within the vertical space between the horizontal planes containing the top and bottom of the motor. 110

4. In a mining machine of the class described, the combination of a bed frame hav- 130

ing suitable carriage feeding mechanism thereon, a carriage mounted on said bed frame to move forward and backward therealong, an endless chain cutting apparatus on said carriage, a suitably housed electric motor supported on said bed frame and having its armature shaft arranged longitudinally thereof and suitably secured to said carriage, and shafting and gearing arranged entirely at one end of said motor housing and comprising a vertically disposed shaft connected by bevel gearing with said armature shaft, two transversely mounted shafts connected together by two trains of differently speeded gears, each 10 of said transverse shafts being suitably connected to the said carriage feeding mechanism on the bed frame, one of them being arranged to transmit power to advance the carriage at relatively slow speed, and the other 20 of them being arranged to transmit power to cause the reverse travel of the carriage at a greater speed, and a sprocket wheel on said vertically disposed shaft for driving said endless chain cutting apparatus.

5. In a mining machine, the combination with the cutting apparatus and the carriage of the bed frame, having the top longitudinal bars A', and the bottom bars A and the front connecting cross bars B, having the relatively 30 wide portion to which the said top bars are secured and the relatively narrow depending portion to which the said bottom bars are secured, substantially as set forth.

6. In a mining machine, the combination 35 with the cutting apparatus and the carriage, of the bed frame having the top longitudinal bars A', the bottom bars A, and the end cross bar B, having the relatively wide portion to which the said top bars are secured, and the 40 depending standards d' adapted to have the said bottom bars secured thereto and to receive between them the thrust bar of the cutting apparatus and fitted with the detachably secured plate B' upon which the said 45 thrust bar is adapted to bear, substantially as set forth.

7. In a mining machine of the class described, the combination of a bed frame having carriage feeding mechanism thereon, a 50 carriage mounted on said bed frame to move forward and back therealong, an endless chain cutting apparatus on said carriage, a suitably housed electric motor mounted on said bed frame and suitably secured to said carriage, said motor having the axis of its armature shaft disposed in a horizontal 55 plane, and shafting and gearing arranged entirely at one end of said motor housing and comprising a vertically disposed shaft connected through bevel gearing with the said armature shaft, two horizontally disposed transversely mounted shafts having their axes of rotation in substantially the same vertical plane between the said front end of said motor housing and the said vertically disposed shaft, one of said transverse shafts being suitably connected at either end to said carriage feeding mechanism on the bed and geared to the other one by two trains of differently speeded gearing, and the latter being suitably geared to said 125 vertically disposed shaft, and a sprocket wheel on said vertically disposed shaft for driving said endless chain cutting apparatus.

8. In a mining machine of the class described, the combination of a bed frame having carriage feeding mechanism mounted thereon, a carriage mounted on said bed frame to move forward and back therealong, an endless chain cutting apparatus on said carriage, a suitably housed electric motor mounted on said bed frame and suitably secured to said carriage, said motor having the axis of its armature shaft disposed in a horizontal 70 plane, and shafting and gearing arranged entirely at one end of said motor housing and comprising a vertically disposed shaft connected through bevel gearing with the said armature shaft, two horizontally disposed transversely mounted shafts arranged between the said end of the motor housing and said vertically disposed shaft, one 75 of them being geared to said vertically disposed shaft and the other one of them being suitably connected at either end to said carriage feeding mechanism on the bed, and a sprocket wheel on said vertically disposed shaft for driving said endless chain cutting apparatus.

8. In a mining machine of the class described, the combination of a bed frame having carriage feeding mechanism mounted thereon, a carriage mounted on said bed frame to move forward and back therealong, an endless chain cutting apparatus on said carriage, a suitably housed electric motor mounted on said bed frame and suitably secured to said carriage, said motor having the axis of its armature shaft disposed in a horizontal 80 plane, and shafting and gearing arranged entirely at one end of said motor housing and comprising a vertically disposed shaft connected through bevel gearing with the said armature shaft, two horizontally disposed transversely mounted shafts arranged between the said end of the motor housing and said vertically disposed shaft, one 85 of them being geared to said vertically disposed shaft and the other one of them being suitably connected at either end to said carriage feeding mechanism on the bed frame and connected to the first described transverse shaft by alternately operative forward slow speed and reverse high speed gearing, and a sprocket wheel on said vertically disposed shaft for driving said endless chain cutting apparatus.

9. In a mining machine of the class described, the combination of a bed frame having carriage feeding mechanism thereon, a carriage mounted on said bed frame to move forward and back therealong, an endless chain cutting apparatus on said carriage, a suitably housed electric motor mounted on said bed frame and suitably secured to said carriage, said motor having the axis of its armature shaft arranged longitudinally of the 100 said bed frame, and shafting and gearing arranged entirely in front of the front end of said motor housing and comprising a vertically disposed shaft connected through bevel gearing with the said armature shaft, two horizontally disposed transversely mounted shafts having their axes of rotation in substantially the same vertical plane between the said front end of said motor housing and the said vertically disposed shaft, one of said transverse shafts being suitably connected at either end to said carriage feeding mechanism on the bed and geared to the other one by two trains of differently speeded gearing, and the latter being suitably geared to said 105 vertically disposed shaft, and a sprocket wheel on said vertically disposed shaft for driving said endless chain cutting apparatus.

10. In a mining machine of the class described, the combination of a bed frame 110

adapted to rest upon the floor of a mine, a carriage mounted on said bed frame and arranged to move forward and back therealong, a suitably housed electric motor mounted upon said bed frame with its armature shaft disposed longitudinally of said bed frame, said motor being suitably secured to said carriage and having its bottom side arranged closely adjacent to the ground-engaging supports for the bed frame, an endless chain cutting apparatus mounted upon said carriage and arranged entirely in front of said motor housing, and shafting and gearing comprising a vertically disposed shaft connected through bevel gearing with the said armature shaft, two horizontally disposed transversely mounted shafts arranged between the front end of said motor housing and said vertically disposed shaft, one of said transverse shafts being suitably connected to said carriage mechanism on the bed and geared to the other one by two trains of differently speeded gearing, and a sprocket wheel on said vertically disposed shaft for driving said endless chain cutting apparatus, all of said shafting and gearing being confined at the front end of said motor housing within the vertical space between the horizontal planes containing the top of said housing and the said ground-engaging supports of the bed frame.

11. In a mining machine of the class described, the combination of a bed frame having carriage feeding mechanism thereon, a carriage mounted on said bed frame to move forward and back therealong, an endless chain cutting apparatus on said carriage, a suitably housed electric motor mounted on said bed frame, suitably secured to said carriage and having its armature shaft disposed in a horizontal plane, and shafting and gearing arranged entirely in front of the front end of said motor housing and comprising a vertically disposed shaft, a bevel gear secured to said vertical shaft, gearing interposed between said bevel gear and said armature shaft, a horizontally disposed carriage moving shaft transversely mounted below said bevel gear and between the front end of said motor housing and said vertical shaft and suitably connected at either end with said carriage feeding mechanism on the bed frame, a horizontally disposed intermediate shaft transversely mounted above said bevel gear and connected with said carriage moving shaft by two trains of differently speeded gearing, worm gearing connecting said intermediate shaft with the vertical shaft, and a sprocket wheel on said vertical shaft for driving said endless chain cutting apparatus.

12. In a mining machine of the class described, the combination of a bed frame, a suitable cutting apparatus, a motor supported on said bed frame and arranged to slide forward and back therealong, a plat-

form F arranged adjacent to one end of said motor and supported on said bed frame to slide forward and back thereon, means for detachably connecting said platform to the motor, and power transmitting mechanism supported by said platform for moving said motor and platform together along the bed frame.

13. In a mining machine of the class described, the combination of a bed frame, a suitable cutting apparatus, a motor supported upon said bed frame and arranged to slide forward and back therealong, a platform F arranged adjacent to the front end of said motor and supported on said bed frame to slide forward and back thereon, means for detachably connecting said platform to the motor, and power transmitting mechanism supported by said platform for actuating the said cutting apparatus and moving the said motor and platform F together along the bed frame.

14. In a mining machine, the combination of a bed frame, a motor supported on the bed frame and adapted to move forward and back thereon, and a gearing supporting platform arranged adjacent to the motor, supported on the bed frame to move forward and back thereon and detachably connected to said motor whereby either the motor or the gear supporting platform may be dismounted without dismounting the other.

15. In a mining machine, the combination of a bed frame, a motor supported on the bed frame and adapted to move forward and back thereon, a gearing and shafting supporting platform arranged adjacent to the motor, detachably connected therewith and supported on said bed frame to move forward and back thereon, whereby either the said platform with the parts carried by it, or the motor may be dismounted from the bed frame without dismounting the other, a cutter carrier secured to said platform, and gearing and shafting mounted on said platform and connected with said cutter carrier and with said bed frame.

16. In a mining machine, the combination with a cutting apparatus adapted to move forward and back on a bed frame and having a thrust bar, of a bed frame having top longitudinal bars A', and a front connecting cross bar B, said cross bar having the relatively wide upper portion to which the said top bars are secured, and the relatively narrowed depending portion having a recess adapted to receive the thrust bar of said cutting apparatus, and the detachably secured plate B' upon which the said thrust bar is adapted to bear.

17. In a mining machine, the combination with a bed frame having top longitudinal bars, bottom longitudinal ground-engaging supporting bars and suitable connecting bars and braces, of a carriage mounted upon said

6
top longitudinal bars of the bed frame to move forward and back therealong, a suitably housed electric motor similarly mounted upon said bed frame and suitably secured to 5 said carriage with its armature shaft arranged longitudinally of said bed frame and having its under side depending beneath said top longitudinal bars to a point closely adjacent to the said ground-engaging supports 10 for the bed frame, so as to travel forward and back in a horizontal plane closely adjacent to the floor of the mine, a cutting apparatus supported by said carriage and arranged entirely in front of the motor housing, and 15 shafting and gearing connecting said motor with said bed frame and cutting apparatus for moving the carriage along the bed frame and actuating the cutting apparatus, respectively, all of said shafting and gearing being

arranged entirely in front of the said motor 20 housing and confined within the vertical space between the horizontal planes containing the ground supports of the bed frame and the top of the motor.

In testimony whereof I, ALEXANDER 25 PALMROS, affix my signature in the presence of two witnesses.

ALEXANDER PALMROS.

Witnesses to Alexander Palmros:

LEOTA I. SAYLOR,
R. GROS. HUTCHINS.

In testimony whereof I, the said EDWARD L. HOPKINS affix my signature in the presence of two witnesses.

EDWARD L. HOPKINS.

Witnesses to Edward L. Hopkins:

R. GROS. HUTCHINS,
EMMA L. VAN DERVEER.
